METHOD OF MAKING COLLARS

Thomas Dow Ainslie, Metuchen, N. J., assignor to Phillips-Jones Corporation, New York, N. Y., a corporation of New York

Application March 2, 1955, Serial No. 491,558

1 Claim. (Cl. 28—72)

This invention relates to the manufacture of collars, and particularly to the type of collar usually employed on men's shirts. One of the objects of the invention is to provide a method and means by which these collars can be easily manufactured in a manner to insure a well-made, inexpensive and uniform product.

At the present time, collars of the type to which the present invention relates, are made from a lengthy web or strip of textile fabric of relatively narrow width, approximately the width of the collars which are made from this strip. The strip might be said to be ribbon-like in width.

The bleaching, dyeing, and other processing of a narrow-width fabric of this kind is such as to often require special apparatus and treatment, as distinguished from the treatment and processing of wide piece goods, such as that from which shirts are made. As a result, care must be exercised in the processing of the strips of fabric from which the collars are made, in order to insure uniformity of appearance and coloring, and to provide a match with the shirting from which the shirts are made and to which the collars are to be attached.

It is accordingly an object of the present invention to provide a means and method for producing collars, and in which a plurality of collar-width sections of the fabric shall be integrally joined in the form of a relatively wide piece of fabric which can be unitarily handled, bleached, dyed or otherwise treated by apparatus and methods employed for the treatment of shirting or any other relatively wide textile sheet material.

It has also been found that when the collars are produced from narrow-width strips or from independent ribbon-like tapes or webs of fabric, and which webs are provided along one marginal edge with areas having a reduction in threads, to thereby produce a fold line area for the collars, there is a tendency for such narrow strips to distort in a manner to cause the edge of the fold line area to depart from straight and to assume a curved line. This warpage of the strip requires special handling when the narrow fabric is processed if the arc is to be maintained reasonably constant. Otherwise, it will be pulled out, causing excessive distortion of the collar after washing.

It is therefore another object of the invention to provide a fabric piece in which a plurality of the collar-producing strips are integrally arranged in side-by-side relationship, with the fold line area on one strip in juxtaposition to the fold line area on the adjacent strip, thus placing the so-called "top-edge" portion of one strip in juxtaposition to the "top-edge" of an adjacent strip. This arrangement is such that the tendency of any one strip in the multi-strip piece of fabric to laterally distort will be resisted by its neighboring strips, so that the strips, when separated from the piece by a slitting machine, will be straight and true and devoid of lateral warpage.

It is still another object of the invention to provide a method of making collars in which a plurality of relatively narrow collar-producing strips are simultaneously

2

woven in the form of a wide fabric piece, with the strips thereof arranged in side-by-side relationship and separated by elongated bands of reduced-thread incorporation, and through which areas separation of the strips is effected to thus provide each strip with a longitudinal marginal edge portion constituting a fold line area for the collars subsequently fabricated from the strip.

With these and other objects to be hereinafter set forth in view, I have devised the arrangement to be described and more particularly pointed out in the claim appended hereto.

In the accompanying drawing, wherein all illustrative embodiment of the invention is disclosed,

Fig. 1 is a face view of a strip of fabric of the character used at the present time for the fabrication of shirt collars;

Fig. 2 is a face view of a section of the wide pieces from which the collar strips are to be made in accordance with the present invention, and

Fig. 3 shows one of the strips produced from the fabric shown in Fig. 2.

In Fig. 1 is shown a short section of the lengthy, relatively narrow strip of woven textile fabrics from which one piece collars for shirts are made from at present.

Such strip is usually about three inches in width and is selvaged along both of its longitudinal edges as indicated at 2 and 3. Adjacent to one of these longitudinal edges is provided an area indicated at 4 which constitutes the fold line area for the collar. This area usually contains less threads than the remainder of the strip in order to facilitate the folding down of the collar on a line extending along said area.

When strips are made in the narrow form just described, special apparatus must be provided for handling them and applying the bleaching, dyeing and other treatments, as distinguished from the similar treatment of wide piece goods. Moreover, it has been found that such narrow strips exhibit a tendency to warp or curve, so that as a result, the strip deviates from straight and this is detrimental to collar production.

In the embodiment of the invention as disclosed in Fig. 2, the strips from which the collars are produced, are integrally joined in connected side-by-side relation, in the form of a wide sheet or piece of fabric 5, a relatively small section of which is shown in the drawing. The fabric sheet is divided at equally-spaced intervals by bands 8 of reduced-thread content, which bands, when split longitudinally and centrally along the dividing lines indicated at 10, produce the fold-line areas 11 for the tops of two adjacent strips, one of which is shown in Fig. 3. The dividing-line, down the centers of the fold-line areas 8, is defined by narrow webs 9 of very materially-reduced thread content, thus facilitating the slitting of the fabric along these lines.

Located alternately to the bands 8 are relatively narrow bands 7, which are also adapted to be slit lengthwise on the lines 10, to produce the edgings along that edge of the collar which is known in the trade as the "top edge," but in reality is the lower edge of the collar when the same is in its turned-down position of wear attached to the shirt.

When the sheet fabric 5 is slit along the lines 10, and this is easily done by a slitting machine of any known type, a plurality of the separated strips 6 will result. This separation of the sheet 5 into the strips 6 is done after the sheet 5 is bleached, dyed or otherwise subjected to treating processes so that any effect that such treatments might have on the fabric will be had while the fabric is in the piece as distinguished from the separate narrow strips in which it is usually treated. Hence, when the strips are severed from the sheet they have been treated so the possibility of the strips warping or deviating from

the straight by treatment will be very materially decreased.

After the strips are cut out from the sheet, they appear as shown in Fig. 3, and the methods normally followed in producing the collars from these strips can then be pursued in the usual manner.

By weaving the strips in the single wide piece, as shown in Fig. 2, with an arrangement in which the fold area of one strip is in juxtaposition to the fold area of the adjacent strip and with the second edge of a strip adjacent to the second edge of the next strip, a further resistance to distortion of the several strips in the sheet takes place. Therefore, again an advantage of producing the strips in integral connection and in side-by-side relation in a wide piece, is present.

While I have herein shown in Fig. 2, only a few of the strips 6 in connected relation in the sheet, it is to be understood that this is only illustrative, since the sheet may be made very wide, having possibly a dozen or more strips according to the capability of the looms on which the fabric is made, or the facilities at hand for the subsequent slitting of the wide piece.

Having described a single embodiment of the invention,

it is obvious that the same is not to be restricted thereto but is broad enough to cover all structures coming within the scope of the annexed claim.

What I claim is:

The method of making collars consisting in weaving a relatively wide piece of textile fabric in a manner to produce in said piece a plurality of equally-spaced, parallel division bands of reduced-thread content, severing the fabric down the longitudinal center line of each of the bands to thereby separate the piece into a plurality of strips, each of said strips having at one of its longitudinal edges a portion of the reduced-thread band to thereby provide an easily-foldable, top-edge area along the upper edge of each of the collars to be formed from each strip, and in cutting collars from each strip in a manner to incorporate along the top edge of each of the collars the reduced-thread portion of the band.
